LOOSE LEAF BINDER

John Potts, Chicago, Ill., and George Lynwood Logan, Cleveland, Ohio, assignors to Wilson-Jones Company, Chicago, Ill., a corporation of Massachusetts

Application August 16, 1939, Serial No. 290,380

7 Claims. (Cl. 129—1)

This invention relates to a loose leaf binder and more particularly to the sheet retaining mechanism mounted in a carrying case adapted to carry a substantial bulk of material, such as catalogs, in pockets adjacent the sheet retaining mechanism.

Loose leaf binders of this general type are quite well known in the art, but they have the disadvantage that when the pockets are filled the sheets impaled on the sheet retaining mechanism cannot lie flat when the binder is opened. Heretofore it has been deemed necessary to provide binders of this type with a wide binding back to insure a pleasing contour to the back when the binder is heavily loaded.

It is an object of this invention to provide simple and efficient means for mounting a sheet retaining mechanism in a carrying case so that the sheets may lie flat when the case is opened regardless of the thickness of the material carried in the pockets of the case. It is a further object of this invention to provide a loose leaf binder with pockets on the inside of its cover members and sheet retaining mechanism arranged in such a manner that the binder does not require a wide binding back. Other objects of this invention will become apparent upon reading the following description, taken in conjunction with the accompanying drawings, in which

Figure 1 is a perspective view of a loose leaf binder embodying the invention;

Figure 2 is a cross sectional view taken along the line II—II of Figure 1;

Figure 3 is a fragmentary perspective view of the binder in open position;

Figure 4 is a view, partly in section and partly in elevation, taken along the line IV—IV of Figure 3; and

Figure 5 is a longitudinal view, partly in section and partly in elevation, taken along the line V—V of Figure 4.

In the drawings the reference numeral 2 indicates a carrying case comprising a back 3 and a pair of cover members 4. The cover members are provided with handles 5 and are connected by flaps 6 joined by means of a slide fastener 7. It will be understood that although the carrying case illustrated has handles and a slide fastener these features are not essential, and the advantages of the invention may be realized with any case having a back and two cover members.

Each cover member 4 is provided with a pocket formed by a side wall 8 secured to the cover member by means of edge gussets 9 and a gusset

10 forming the base of the pocket. The pockets are adapted to receive catalogs or similar material 11 and are spaced apart a sufficient distance to permit the securement of sheet retaining means therebetween. The side walls 8 of the pockets are provided with flaps 12 which extend beyond the base 10 and are lapped and secured together to form a floating support for a suitable sheet retaining mechanism. Although it is preferred to form this support by lapping flaps extending from the side walls 8, it is obvious that the flap might extend from only one wall and be secured to the other, or a separate piece of material might be secured to the side walls 8 or to the base gussets 10 adjacent the walls 8. It is also possible to form both side walls 8 from a single sheet of material, but this structure is not preferred because of its expensiveness.

20 The preferred form of sheet retaining mechanism is a conventional ring metal 13 although a pair of flaps carrying sheet retaining post metals, or any other desired form of sheet retaining mechanism, could be used. The ring metal 13 comprises a plurality of divided ring sections 14 and a pair of triggers 15 operable to open and close the ring sections to permit the impalement or removal of a plurality of apertured sheets 16. The ring metal is secured to the flaps 12 by means of a binding back 17. The back of the case may be provided with a reinforcing strip 18 of any suitable material to prevent excessive wear from the contact of the metal binding back.

30 When the case is closed the sheet retaining means rests on the bottom of the case and the contents of the pockets are disposed above the rings as shown in Figure 2. No wide binding back is required because the back 3 of the case will assume a natural curve regardless of the bulk of material 11. When the case is opened, as shown in Figures 3 and 4, the securement of the flaps 12 to the pockets causes the sheet retaining mechanism to be raised relative to the back 3. The elevation of the sheet retaining mechanism is directly proportional to the bulk of material 11 so that the sheets 16 always lie flat when the binder is opened regardless of the thickness of the contents of the pockets.

40 45 50 Although we have described one embodiment of our invention in detail, it will be understood that the description thereof is illustrative, rather than restrictive, as many details may be modified or changed without departing from the spirit or scope of the invention. Accordingly, we do not

desire to be restricted to the exact details of construction described, except as limited by the appended claims.

We claim:

1. In a loose leaf binder, a pair of cover members connected to an intermediate back member, a pocket member secured to each of said cover members, a flap member connected to said pocket members, and sheet retaining means secured to said flap member.

2. In a loose leaf binder, a pair of cover members, a pocket secured to each of said cover members, one wall of each of said pockets extending beyond the base thereof, and a ring metal secured to said extending portions of said walls.

3. In a loose leaf binder, a pair of covers connected to an intermediate back member, each cover being provided with a pocket, sheet retaining means between said pockets, and means for adjusting the position of said sheet retaining means in accordance with the thickness of the contents of said pockets.

4. In a loose leaf binder, a pair of covers connected to an intermediate back member, each cover being provided with a pocket, a ring metal movably mounted in said binder between said pockets, and means for moving said ring metal proportionately to the thickness of the contents of said pockets so as to permit sheets carried by said ring metal to lie flat whenever said binder is opened.

5. In a loose leaf binder, a back member, a

pair of covers connected thereto, each of said covers being provided with a pocket, sheet retaining means movably mounted in said binder, and means engaging said pockets and said sheet retaining means, said second mentioned means being adapted to move said sheet retaining means perpendicularly to said back member in accordance with the thickness of the contents of said pockets automatically when said binder is opened to permit sheets carried by said sheet retaining means to lie flat.

6. In a loose leaf binder, a pair of cover members connected to an intermediate back member, a pocket secured to each of said cover members, sheet retaining means positioned between said pockets, and means automatically raising said sheet retaining means to substantially the same level as the upper walls of said pockets when said covers are opened.

7. In a loose leaf binder, a back member, a pair of cover members extending from opposite edges of said back member, a pocket secured to each of said cover members, sheet retaining means positioned between said pockets and adapted to rest on said back member when said pockets are empty, and means for raising said sheet retaining means to substantially the level of the contents of said pockets when said pockets are filled and the binder is opened.

JOHN POTTS.

GEORGE LYNWOOD LOGAN.
